BOW DRAWING AND RELEASING DEVICE

Frank E. Eicholtz, San Diego, Calif., assignor to
Warren Beckwith

Application April 17, 1944, Serial No. 531,355

4 Claims. (Cl. 124—35)

1

My invention relates to a device to facilitate the releasing of the bow when using a bow string or arrow either in archery or otherwise and the objects of my invention are:

First, to provide a releasing device of this class which provides means whereby the bow string will go straight to the center of the bow;

Second, to provide a releasing device of this class which provides for a clean sharp release of the bow strings;

Third, to provide a device of this class which protects the hands of the user of the bow and arrow;

Fourth, to provide a device of this class which is so shaped and arranged that it is a natural fit to the hand and requires only slight tilting of the hand in a natural way for maximum results;

Fifth, to provide a device of this class which provides a natural hand fitting shield for the hand and guide for positioning the arrow; and

Sixth, to provide a device of this class which is very simple and economical of construction, easy to operate, efficient in its action and which will not readily deteriorate or get out of order.

With these and other objects in view as will appear hereinafter, my invention consists of certain novel features of construction, combination and arrangement of portions as will be herein-after described in detail and particularly set forth in the appended claims, reference being had to the accompanying drawings and to the characters of reference thereon which form a part of this application in which:

Figure 1 is a diagrammatic side elevational view of my bow drawing and releasing device shown positioned in the hand of the user and showing the bow and string in relation therewith before releasing, all except the device being shown by dash lines; Fig. 2 is a similar view showing the device in position just after release and Fig. 3 is an isometric view of the device alone.

Similar characters of reference refer to similar parts throughout the several views of the drawings.

My bow drawing and releasing device in its preferred form consists of a main portion 1 which is provided with a curved extended portion 2 which is arranged to fit the palm of the hand at the base of the thumb, as shown best in Figs. 1 and 2 of the drawings. It is provided with two finger receiving grooves 3 and 4 at its opposite end which are adapted to receive the first and second fingers of the hand of the user as shown in Figs. 1 and 2 of the drawings. It is provided with a side inwardly curved portion 5 which is adapted

2 to be grasped by the third and fourth fingers of the hand as shown in Figs. 1 and 2 of the drawings. It is provided on its normally upper side with a curved portion 6 which is arranged to substantially conform to the curve of the thumb when in position, as shown in Figs. 1 and 2 of the drawings. Near the forward upper side of this device is an upwardly extending lug portion 7 leaving an offset portion 8, which forms a portion 10 for engagement of the string S, as shown in Figs. 1 and 2 of the drawings by dash lines. This portion 7 is curved from the portion 8 forwardly and downwardly slightly at 9 to provide a smooth relief surface for the string upon release. This device is also provided in its right side with a groove 10 which is of proper size to receive the one side of the string receiving end of the arrow and it will be noted that it extends backwardly some distance past the string engaging offset portion 8, as shown best in Fig. 3 of the drawings.

The operation of my bow drawing and releasing device is substantially as follows:

The device is held in the hand substantially as shown in Fig. 1 of the drawings with the string "S" resting against the string engaging portion 8 and the thumb positioned on the top portion of the string engaging end of the arrow, all as shown in Fig. 1 of the drawings. In this position the string is drawn together with the arrow springing the bow, the rear portion of the device being held downwardly in the proper position so that the string is held against the engaging portion 8 until the bow is drawn sufficiently. In releasing the hand with the device is shifted so that the front end is lowered and the rear end raised slightly which is done slowly and gradually until the string leaves the string engaging portion 8 and passes over the upper surface 7, as shown in Fig. 2 of the drawings, thus clearing the support 8 and the upper surface of the portion 7 defining a clear sharp relief as the string goes straight to the center of the bow providing greater accuracy in shooting.

Though I have shown and described a particular device with particular positions, I do not wish to be limited to this particular arrangement of portions, but desire to include in the scope of my invention the construction, combination and arrangement substantially as set forth in the appended claims.

Having thus described my invention, what I claim as new and desire to secure by Letters Patent is:

1. In a bow string drawing and releasing device, 55 a body member having an index finger drawing

groove on its front end adapted to accommodate the index finger of a person's hand, said body portion having a stringing engaging ledge adjacent said index finger groove parallel thereto, said body portion having a hand palm engaging portion extending transversely to the engaging surface of said string engaging ledge.

2. In a bow string drawing and releasing device, a body member having an index finger drawing groove on its front end adapted to accommodate the index finger of a person's hand, said body portion having a string engaging ledge adjacent said index finger groove parallel thereto, said body portion having a hand palm engaging portion extending transversely to the engaging surface of said string engaging ledge, said body provided with an arrow receiving groove at one end of said ledge at right angles to said ledge and said index finger drawing groove.

3. In a bow string drawing and releasing device, a body member having an index finger drawing groove on its front end adapted to accommodate the index finger of a person's hand, said body portion having a string engaging ledge adjacent said index finger groove parallel thereto, said body portion having a hand palm engaging portion extending transversely to the engaging surface of said string engaging ledge, said palm engaging portion having a convex surface portion extending from said ledge backwardly and provided with opposed concave third and fourth finger engaging portions whereby said palm en-

gaging portion may be gripped at its rear end between the base of a person's thumb and the third and fourth finger of the same hand.

4. In a bow string drawing and releasing device, 5 a body member having an index finger drawing groove on its front end adapted to accommodate the index finger of a person's hand, said body portion having a string engaging ledge adjacent said index finger groove parallel thereto, said body portion having a hand palm engaging portion 10 extending transversely to the engaging surface of said string engaging ledge, said body provided with an arrow receiving groove at one end of said ledge at right angles to said ledge and said index finger drawing groove, said arrow groove being adjacent said index finger groove and permitting an arrow engaging the string on said ledge to be gripped between the thumb and index finger of a person's hand.
